ATTORNEY

UNITED STATES PATENT OFFICE

CARL OTTO, OF ESSEN-RUHR, GERMANY

VERTICAL COKE OVEN

Application filed January 7, 1927, Serial No. 159,611, and in Germany February 15, 1926.

In the vertical regenerative chamber ovens the heating walls of which are subdivided so as to form a plurality of vertical heating flues, these heating walls generally are supplied with the flames from bottom to top during one period and from top to bottom during the subsequent period. If coke ovens of this type are to be heated by different kinds of gas, or if coals of different properties are to be distilled or coked therein, difficulties arise frequently as to the heating of the heating walls, as it is desirable according to the nature of the heating gas or of the coal to be heated, to heat more strongly either the upper or lower portion of the heating walls. With continuously operating ovens the mentioned heating method further suffers from the drawback that the oven, when heated from top to bottom, becomes too hot in its upper portion, whereby the fed coal is heated too quickly and has the tendency of hanging in the upper portion of the chamber.

Now the invention hereinafter described offers in a very simple manner the possibility of obtaining on the one hand the proper main combustion, that means the union of heating gas and air, within the vertical heating flues at a certain distance remote from the flue ends, and, on the other hand, causing a combustion to take place in the horizontal heating channels, the extent of which combustion may be regulated as desired.

In order to allow of my invention to be more easily understood, a preferred embodiment of the same is illustrated by way of example in the drawing which accompanies and forms part of this specification. In this drawing:

Fig. 1 is a vertical longitudinal section through the oven battery,

Fig. 2 is a vertical section on line 2—2 of Fig. 1, and

Fig. 3 is a horizontal section on line 3—3 of Fig. 2.

Referring now to these figures, *a* denotes the vertical oven chambers which have arranged between them the heating walls *b* subdivided so as to form a plurality of vertical heating flues. The heating gas and the air are

conducted to the heating flues through horizontal combustion channels *c* and *d* from the gas and air regenerators through supply conduits *c'*, *d'*, respectively. As it will be seen, the channels *c* and *d* are provided at the tops and bottoms of the heating flues and constitute separate heating channels extending horizontally over the whole length of the heating wall. They have upper and lower passages *e* and *f* opening into the heating flues providing admission ports between the horizontal channels and the vertical flues. In order to cause a certain advance combustion to take place in the channels *c* and *d*, prior to the main combustion in the vertical flues, damper bricks *h*, see Figs. 2 and 3, are arranged in the partitions *g* separating every pair of channels *c* and *d*. As Fig. 2 shows, these damper bricks *h* are superimposed crosswise, and their mutual position may be adjusted from perforations *i* provided in the cover of the oven masonry. According to the amount of the angle at which the bricks *h* are adjusted relatively to the partition *g*, a greater or less passage of heating gas and air may take place into the companion channels *c* and *d*, whereby the desired combustion in these channels is obtained. With heating gases which give but a comparatively short flame when mixed with the combustion air, it may further be desirable, to distribute the union of gas and air over a greater space within the heating flues. To this end partitions *k*, see particularly Figs. 1 and 2, are built in the heating flues which partitions project into the flues to a certain extent from above and below. These partitions *k* may further be provided with holes *k'*, in order to also have a certain combustion at the top and bottom ends of the heating flues brought about by the mutual transition of gas and air through the holes *k'*.

With ovens of a type in which the heating walls are flamed always in one direction, the damper bricks *h* and partitions *k* are arranged only in those ends of the heating flues where the supply of the agents of combustion takes place.

My invention is further particularly adapted to be employed in continuously operating

vertical chamber ovens, as with a suitable adjustment of the damper bricks h and suitable arrangement of the upper partitions k the main combustion begins only a certain distance below the top end of the heating flues and care is taken, on the other hand, to provide the temperature required to pre-heat the coal in the upper chamber portions by the described partial combustion, prior to the main combustion in the vertical flues.

My invention thus enables different desired high temperature to be obtained in the different levels of the heating walls, as this was the case hitherto only with vertical chamber ovens having horizontal flues. At the same time the known advantages are obtained which result from the provision of vertical heating flues in comparison with horizontal ones.

What I claim and desire to secure by Letters Patent, is:

1. In a coke oven having a coking chamber, a heating wall with vertical heating flues for said chamber, a horizontal combustion channel forming part of the heating wall and communicably connected to the vertical heating flues, means for conducting gas and air separately and simultaneously to said channel and means for adjusting the amount of gas and air supplied so as to enable an adjustable combustion to take place in said channel.

2. In a coke oven having two coking chambers, a heating wall therebetween provided with vertical heating flues for said chambers, horizontal combustion channels forming part of the heating wall, each of said channels being communicably connected to the vertical heating flues of the wall at one end of said flues, and means for conducting air and gas separably and simultaneously to each of the channels.

3. In a coke oven having two coking chambers and a heating wall therebetween provided with vertical heating flues for said chambers, a pair of horizontal combustion channels forming part of the heating wall, said channels being communicably connected to one end of the flues of the heating wall, an apertured partition separating said channels, a damper arranged in the aperture of said partition, and means for supplying gas and air so as to enable a passage of gas and air to take place into each of said channels.

4. In a coke oven having two coking chambers and a heating wall therebetween provided with vertical heating flues for said chambers, a pair of horizontal combustion channels forming part of the heating wall, said channels being communicably connected to one end of the flues of the heating wall, an apertured partition separating said channels, a damper arranged in the aperture of said partition, means for supplying gas and air so as to enable a passage of gas and air to

take place into each of said channels, and means arranged in the vertical heating flues for displacing the combustion in said flues to a place located at a distance from their ends.

5. In a coke oven having two coking chambers and a heating wall therebetween provided with vertical heating flues for said chambers, a pair of horizontal combustion channels forming part of the heating wall, admission ports communicably connecting the channels to one end of each of the flues of the heating wall, a pair of supply conduits for supplying gas and air respectively to the horizontal channels, an apertured partition separating the channels, a damper arranged in the aperture of said partition so as to enable a passage of gas and air to take place into each of said horizontal channels, and a vertical partition projecting into each vertical heating flue, from between the admission ports at one end of each flue.

6. In a coke oven having two coking chambers and a heating wall therebetween provided with vertical heating flues for said chambers, a pair of horizontal channels forming part of the heating wall, admission ports communicably connecting the channels to one end of each of the flues of the heating wall, a pair of supply conduits for supplying gas and air respectively to the horizontal channels, an apertured partition separating the channels, a damper arranged in the aperture of said partition so as to enable a passage of gas and air to take place from the supply conduit into each of said horizontal channels, and a vertical partition projecting into each vertical heating flue, from between the admission ports at one end of each flue, said vertical partitions being constructed so as to enable combustion to take place at the ends of said heating flues.

7. In a coke oven having two coking chambers and a heating wall therebetween provided with vertical heating flues for said chambers, a pair of horizontal channels forming part of the heating wall, admission ports communicably connecting the channels to one end of each of the flues of the heating wall, a pair of supply conduits for supplying gas and air respectively to the horizontal channels, an apertured partition separating the channels, a damper arranged in the aperture of said partition so as to enable a passage of gas and air to take place from the supply conduits into each of said horizontal channels, and a vertical partition projecting into each vertical heating flue, from between the admission ports at one end of each flue, said vertical partitions being provided with crossholes extending therethrough.

8. In a coke oven having two coking chambers and a heating wall therebetween provided with vertical heating flues for said chambers, horizontal channels forming part

of the heating wall, each communicably connected to and adapted to supply gas and air to said heating flues at one end thereof, a conduit for supplying gas and a conduit for supplying air to said horizontal channels, an apertured partition separating the supply conduits and separating the horizontal channels, and a damper arranged in said partition so as to enable a passage of gas and air to take place from the supply conduits into each of said channels.

9. In a coke oven having two coking chambers and a heating wall therebetween provided with vertical heating flues for said chambers, upper horizontal channels, and lower horizontal channels forming part of the heating wall, each communicably connected to and adapted to supply gas and air to said heating flues, an apertured partition separating the upper horizontal channels, an apertured partition separating the lower channels, supply conduits for supplying gas and air to said horizontal channels, respectively, and dampers arranged in the apertures of the partitions so as to enable a passage of gas and air to take place from the supply conduits into each of the upper and lower horizontal channels.

In testimony whereof, I have signed my name to this specification.

CARL OTTO.
